(57) **CLAIM**

I claim the ornamental design for a display screen with a graphical user interface, as shown and described.

DESCRIPTION

FIG. 1 is a view of a display screen with a graphical user interface showing the new design; and,

FIG. 2 shows another embodiment thereof.

Broken lines show the display screen and parts of the display screen with a graphical user interface which form no part of the claimed design.

1 Claim, 2 Drawing Sheets
